UNITED STATES PATENT OFFICE.

JOSEPH S. SACKETT, OF NEW HAVEN, CONNECTICUT, ASSIGNOR OF ONE-HALF TO JANE HALLIWELL, OF SAME PLACE.

MECHANICAL MOVEMENT.

SPECIFICATION forming part of Letters Patent No. 284,491, dated September 4, 1883.

Application filed July 30, 1883. (No model.)

To all whom it may concern:

Be it known that I, JOSEPH S. SACKETT, of New Haven, in the county of New Haven and State of Connecticut, have invented a new Improvement in Mechanical Movements; and I do hereby declare the following, when taken in connection with accompanying drawing and the letters of reference marked thereon, to be a full, clear, and exact description of the same, 10 and which said drawing constitutes part of this specification, and represents a plan view.

This invention relates to a device for converting reciprocating into rotary movement, and while applicable to many uses, is specially 15 adapted to that class of ruffling attachments for sewing-machines which are designed to produce a scallop-like edge on the ruffle, and as indicated in my application for Letters Patent filed April 28, 1883; and the invention 20 consists in a vibrating lever, one arm of which substantially surrounds a toothed ratchet and carries pawls of the peculiar construction, hereinafter described, whereby each vibration of the lever imparts a corresponding rotation to 25 the ratchet.

A represents the ratchet, hung upon a pivot, *a*, to which the rotary movement is to be imparted. B is a lever hung upon a pivot, *b*. One arm of the lever is bifurcated to form two 30 prongs, *d e*, between which plays any device to impart movement to said lever—such, for illustration, as the bell-crank lever on a sewing-machine ruffler—or the vibratory movement of the lever may be otherwise imparted. The 35 other arm of the lever is made of ring shape and surrounds the ratchet A, the opening in the ring being considerably larger than the ratchet. Upon the inner side of this ring two pawls, *f g*, are arranged, one upon each side of the ratchet 40 A, the nose of one engaging the teeth in one direction and the other in the opposite direction. These pawls are formed at their pivot end with a circular head, *h*, and upon the inner edge of the ring seats for these heads, in 45 corresponding shape, are formed. The recesses to form these seats extend a little more than half around the head of the pawls, so that when the pawls are dropped into their seats they

are retained by the surrounding part of the ring, and without the introduction of the pivots 50 through the head. Opposite the pawls a single spring is introduced, having two arms, *i l*, bearing, respectively, upon the two pawls. Midway of the length of the spring in the inside of the ring part of the lever a recess, *m*, is cut, somewhat more than half a circle, and at that point a partial ring, *n*, is formed in the spring, and so that the ring part or circular bend in the spring will drop into the recess *m* in the lever and thus secure the spring in its position, the arms extending, respectively, onto the backs of the pawls *f g*. Standing in the 55 position shown, with the pawl *g* engaged with a tooth of the ratchet, the movement of the lever to the position indicated in broken lines 60 will cause the pawl *g* to turn the ratchet to the extent of that movement; then the pawl *f* will engage its tooth, as seen in broken lines, and on the return of the lever will correspondingly turn the ratchet. Hence each movement or vibration of the lever imparts a partial rotation to the ratchet, and such rotation 65 may be imparted to whatever device is in connection with the ratchet, so that a step-by-step and rotative movement will thereby 70 be imparted.

I claim—

1. The combination of the lever B, arranged upon a pivot for vibratory movement, the ratchet A, one arm of said lever substantially 80 surrounding said ratchet, the two pawls *f g*, arranged in said lever on opposite sides of said ratchet, and springs to bear upon said pawls, substantially as described.

2. The combination of the lever B, arranged 85 upon a pivot for vibratory movement, the ratchet A, one arm of said lever substantially surrounding said ratchet, the two pawls *f g*, constructed, respectively, with circular heads *h*, and the arm with corresponding circular recesses to more than half surround said circular heads, and springs arranged to bear upon said pawls, substantially as described.

3. The combination of the lever B, arranged 90 upon a pivot for vibratory movement, the ratchet A, one arm of said lever substantially

surrounding said ratchet, the two pawls *fg*, constructed, respectively, with circular heads *h*, and the arm with corresponding circular recesses to more than half surround said circular heads, and the said arm also constructed with a more than half-circular recess, *m*, and with springs *il*, having a corresponding head,

n, to set into said recess *m*, the said springs arranged to bear, respectively, upon said pawls, substantially as described.

JOSEPH S. SACKETT.
